UNITED STATES PATENT OFFICE.

FRANCIS A. HALSEY, OF SWANTON, VERMONT.

SMOKELESS POWDER.

No. 878,726.

Specification of Letters Patent.

Patented Feb. 11, 1908.

Application filed October 16, 1906. Serial No. 339,147.

To all whom it may concern:

Be it known that I, FRANCIS A. HALSEY, a citizen of the United States, residing at Swanton, county of Franklin, State of Vermont, have invented a new and useful Improvement in Smokeless Powders, of which the following is a specification.

The object of my invention is to provide a powder, chiefly for use in the various calibers of fire-arms, which will be smokeless, comparatively safe to manufacture and use with a high explosive power on ignition, and which will not deteriorate on exposure.

It consists of a compound made up of the following elements combined in about the proportions specified:

20	Ammonium picrate	43%
	Barium nitrate	34%
	Potassium picrate	10%
	Ferrocyanid of potassium	1%
	Potassium permanganate	4%
	Finely pulverized wood	8%

These constituents are mixed together in the usual manner, being first finely pulverized, the potassium permanganate being dissolved first in cold water, and all are then intimately incorporated by passing through a kneading machine, in which they are mixed until thoroughly homogeneous, the process 30 being assisted by a small quantity of water. The resultant composition is at this stage in the form of a damp adhesive mass, which is then passed through separating or granulating sieves and dried.

35 It is understood that the exact proportions above specified may be slightly varied

according to the caliber of the fire-arms or guns for which the powder is to be used. The advantage of this composition and process is in the greatly decreased cost of production and safety in manufacture and safety in use.

By the use of potassium permanganate there is chlorin liberated upon the explosion which bleaches the smoke generated by the other ingredients. This will be apparent, when it is considered that I use commercial nitrates in the preparation of my improved powder, and not a chemically pure article. The commercial nitrates all carry a small percentage of chlorin and upon this is based the proportions of the ingredients that I use, for the oxygen and the chlorin bleach the coloring matter in the smoke and destroy it. It may be noted, also, that the powder of the present invention is a bulk powder, that is, it may be loaded measure for measure with black powder. It will be further noted that the reaction of the improved powder is neither acid nor alkaline but neutral.

What I claim and desire to secure by Letters Patent, is—

The herein described granular explosive powder consisting of the following ingredients in about the proportions specified: ammonium picrate, 43%; barium nitrate, 34%; potassium picrate, 10%; ferrocyanid of potassium, 1%, potassium permanganate, 4%, and finely pulverized wood, 8%.

FRANCIS A. HALSEY.
